UNITED STATES PATENT OFFICE.

ANDREW H. KLING AND CHARLES E. FOERCH, OF CLINTON, CONNECTICUT.

HEAT-INDICATOR FOR JOURNAL-BEARINGS.

1,196,701.

Specification of Letters Patent. Patented Aug. 29, 1916.

Application filed November 6, 1915. Serial No. 60,087.

To all whom it may concern:

Be it known that we, ANDREW H. KLING and CHARLES E. FOERCH, citizens of the United States, residing at Clinton, in the 5 county of Middlesex and State of Connecticut, have invented new and useful Improvements in Heat-Indicators for Journal-Bearings, of which the following is a specification.

10 This invention relates to thermostatic alarm devices by means of which an audible signal will be given when the temperature of the surrounding atmosphere in the vicinity of the device rises above a predetermined degree.

15 The primary object of the invention is to provide a thermostatic device that can be readily attached to the structure to be protected and the vital parts of which can be readily gotten to for renewal.

20 Another object of the invention is the novel manner in which one of the electrodes of the device is mounted and allowed to assume an active position, when the temperature in its vicinity reaches a certain degree.

25 The invention consists in the features of construction, combination, and arrangement of parts, hereinafter fully described and 30 claimed, reference being had to the accompanying drawings, in which:

35 Figure 1 is a longitudinal section through a portion of a wheel and its axle showing our device applied thereto, the device being shown in side elevation. Fig. 2 is a vertical section therethrough. Fig. 3 is a horizontal section. Fig. 4 is a detail view of a portion 40 of the device. Fig. 5 is a plan view of a modified form. Fig. 6 is a cross section through Fig. 5.

45 Referring to the drawings and more particularly to the form of our device shown in Figs. 1 to 4, the numeral 1 designates a plug having a threaded extension 2 engaging the threaded bore 3 formed in the hub 4 of the wheel 5, shown mounted upon the usual axle 6. This plug 1 is provided with a centrally arranged passage 7 circular in cross section. The bottom of the passage 7 50 has seated therein a ferrule of insulation 8 upon which seats a mica disk forming a foot bearing for the lower end of an electrode 9 secured to a rod 7^a centrally arranged within the passage 7 and projecting through the

55 cap 10, the latter being threaded upon the upper end of the plug. Insulating the rod 7^a from the cap 10 is a sleeve 11 and bearing upon opposite sides of the sleeve is a collar 12 formed integral with the rod 7^a and nuts 13 threaded upon the upper end 60 of the rod and to which the usual electric wire is attached. The electrode 9 is made of springy material and so formed to have a looped portion 14 which tends to move the curved extremity 15 away from the position in which it is held by means of the solder 16 to a position to engage the wall of the passage 7. In practice, the rod 7^a forms one terminal of the electric circuit while the plug 1, made of any suitable material forms the other terminal of the electric circuit. In view of this arrangement, it will be seen that as soon as the surrounding atmosphere reaches a certain degree, the solder will fuse for releasing the electrode so that the extremity 15 will engage 75 the body of the plug for completing the circuit.

80 In the modified form of our invention, we have shown a disk 17 of porcelain or other suitable insulating material provided with three upstanding posts 18, 19, and 20, the post 18 forming one terminal of an electric circuit while the post 20 forms the other terminal of the circuit. A resilient wire 21 85 has one extremity coiled around the post 20 and secured thereto and tends to move toward the post 18 when the solder 22 securing it to the post 19 fuses in the manner previously set forth.

90 Having described the invention, what is claimed is:

95 1. A thermostatic circuit closer comprising a plug provided with a cylindrical passage, a rod mounted in said passage but insulated from the walls of the passage, a spring electrode secured to said rod and adapted to move into engagement with a wall of the passage, and a fusible element securing said spring electrode to the rod and 100 spacing it from a wall of the passage.

105 2. A thermostatic circuit closer comprising a plug provided with a cylindrical passage, a disk of insulated sheet in the bottom of the passage, a cap threaded on said plug, a cylindrical rod passing through the cap, a spring electrode secured to one extremity of the rod having an intermediate portion

resting on the disk of insulation; and having its remaining extremity arranged to engage the wall of the passage, and fusible means for attaching the last mentioned extremity to the first mentioned extremity of the electrode for normally spacing the last mentioned extremity from the wall of the passage.

In testimony whereof we affix our signatures in presence of two witnesses.

ANDREW H. KLING.
CHARLES E. FOERCH.
